UNITED STATES PATENT OFFICE.

JOHN OTTO RHIEN, OF SANTA CRUZ, CALIFORNIA.

PAVEMENT-MARKING MACHINE.

Application filed November 9, 1922. Serial No. 599,883.

To all whom it may concern:

Be it known that I, JOHN OTTO RHIEN, a citizen of the United States, and a resident of Santa Cruz, county of Santa Cruz, State of California, have invented a new and useful Pavement-Marking Machine, of which the following is a specification.

The present invention relates to improvements in painting machines and has particular reference to a device of the character described that may be used for the purpose of marking pavements or garage floors or the like with guide lines such as are now commonly used on busy city streets to establish safety zones or the like. It is proposed to provide a machine mounted on a truck that will draw a paint line when disposed in an operative position by merely being passed over the pavement on which the line is to be drawn. Further objects and advantages of the device will appear as the specification proceeds.

The preferred form of my invention is illustrated in the accompanying drawing in which Figure 1 shows a side elevation of my device, Figure 2 a vertical section through the same, and Figure 3 a horizontal section through the same taken on line 3—3 of Figure 2. While I have shown only the preferred form of the invention it should be understood that various changes or modifications may be made within the scope of the claims hereto attached without departing from the spirit of the invention.

My device is preferably mounted on a three wheel truck (1) having a suitable frame (2) supported on the front and rear axles (3) and (4) which latter are mounted in suitable wheels (6). Substantially midway between the two axles a transverse tube (7) is supported in the frame closed at both ends by the caps (8). A solid casting (9) preferably of the shape shown in Figures 1 and 2 provided with a central vertical passage (11) engages the tube (7) by means of a sleeve (12) and communicates with the inside of the tube through the port (13). In the upper end of the passage is supported by a threaded engagement (14) the neck (16) of a cylindrical receptacle (17) which is elongated in form and extends upwardly to a considerable height slanting rearwardly as shown in the drawing and closed at its upper end by a suitable lid (18). In the casting is also supported as shown at (19)

a handle (21) which extends in parallel relation to the receptacle and is of sufficient length to allow of the convenient manipulation of the truck.

The casting has supported therein two downwardly extending brushes (22) and (23), the former which is first in order slanting rearwardly while the latter which follows the path of the former occupies a substantially vertical position. The brush (22) extends within operative proximity of a cock (24) communicating with the inside of the tube (7) and controlled by a valve (26) provided with a suitable handle (27) to the extreme end of which is secured a rod (28) supported in parallel relation to the handle (21) and terminating at its top end in a hook (29) of suitable form. The mouth of the cock (24) discharges into a small paint catcher (31) which latter communicates with an internal passage (32) in the first paint brush adapted to deliver the paint at the root of the bristles (33). The weight of the receptacle (17) which is to be filled with liquid paint tends to tilt the casting rearwardly on its pivotal support (7) and the hook (34) supported in the front end of the frame (2) engaging a notch (36) in the casting is used to prevent the receptacle from tilting the casting beyond an operative position.

The brushes are arranged in such a manner that if the receptacle is swung into a vertical position such as indicated in dotted lines in Figure 1 neither of the brushes will touch the pavement surface, the first brush occupying at this time a horizontal position as shown in Figure 1 in dotted lines and the second brush being lifted sufficiently high to clear the pavement.

The operation of the device is very simple. After the receptacle has been filled with liquid paint it is only necessary for the operator to tilt the same into the operative position shown in full lines in Figure 1 securing preferably the casting by means of the hook (34) engaging the notch (36) when both brushes will sweep the pavement surface. When advancing the machine the operator opens the cock (24) by means of the rod (28) and paint is allowed to flow through the paint catcher to the root of the bristles of the first brush from where it will be distributed over the pavement surface, the second brush following the path of the first.

one serving to smoothen the paint. When a certain line is finished the operator tilts the receptacle into the inoperative position shown in dotted lines in Figure 1 in which 5 it may be held by the hook (34) engaging a second upper notch (37) and in this position both brushes clear the surface of the pavement. The operator simultaneously, of course, closes the cock (24) and is now ready 10 to move to the next line to be drawn.

I claim:

1. A painting device for marking pavements and the like comprising a truck, a paint receptacle supported thereon, a brush 15 associated therewith adapted to sweep the ground surface and means for feeding paint from the receptacle into the brush with a second brush supported behind the first brush adapted to follow the same for 20 smoothing the paint.

2. A painting device for marking pavements and the like, comprising a truck, a casting supported thereon having a paint receptacle mounted on the same, a brush supported in the casting adapted to sweep the ground surface, a valve-controlled communication 25 between the receptacle and the brush allowing paint to be fed into the latter and a second brush supported in the 30 casting adapted to follow the first brush for smoothing the paint.

3. A painting device for marking pavements and the like comprising a truck, a casting pivotally supported thereon having 35 a paint receptacle mounted on the same, a brush supported in the front end of the casting slanting downwardly so as to sweep the ground surface, a valve-controlled communication between the receptacle and the 40 brush allowing paint to be fed into the latter, and a second brush supported in the casting adapted to follow the first brush for smoothing the paint, the positions of the 45 brushes being such that they lose contact with the ground surface when the casting is tilted forwardly into an inoperative position.

4. A painting device for marking pavements and the like comprising a truck, a casting pivotally mounted thereon having 50 an elongated receptacle supported on the same with the receptacle slanting upwardly and rearwardly, a handle supported on the casting in parallel relation to the receptacle, 55 two brushes extending downwardly from the casting so as to sweep the ground sur-

face in successive order, a valve-controlled communication between the receptacle and the first brush allowing paint to be fed into the same and a hook supported in the truck 60 adapted to engage either of the two notches in the casting for holding the brushes in an active or an inactive position.

5. A pavement marking machine comprising 65 a truck, a receptacle pivoted thereon adapted to be swung into driving relation with the truck, means associated therewith for feeding paint to the pavement surface and a brush supported in fixed relation to the receptacle for engagement with the 70 pavement surface when the receptacle is held in driving position and clearing the said surface when the receptacle is turned into a vertical position.

6. A pavement marking machine comprising 75 a truck, a casting pivotally supported thereon having an elongated receptacle mounted thereon adapted to be swung into driving relation with the truck, means associated with the receptacle for feeding 80 paint to the pavement surface and a brush extending downwardly from the casting for engagement with the pavement surface when the receptacle is held in a driving position and clearing said surface when the 85 receptacle is turned into a vertical position.

7. A pavement marking machine comprising 90 a truck, a casting pivotally supported thereon having a handle extending therefrom adapted to be swung into driving relation with the truck, an elongated receptacle mounted parallel to the handle having means for feeding paint to the pavement surface associated therewith, and a brush extending downwardly from the casting for 95 engagement with the pavement surface when the handle is held in a driving position, and clearing the said surface when the handle is turned into a vertical position.

8. A pavement marking machine comprising 100 a truck, a paint receptacle pivoted thereon having a brush supported in fixed relation thereto adapted to engage the pavement surface and having means associated therewith for delivering paint to the surface, the brush contacting the pavement surface when the receptacle is held in a rearwardly slanting position, and clearing the said surface when the receptacle is held in a vertical position.

JOHN OTTO RHIEN.
